UNITED STATES PATENT OFFICE.

GEORGE S. BARROWS, OF PROVIDENCE, RHODE ISLAND, ASSIGNEE TO GENERAL FIRE EXTINGUISHER COMPANY, OF PROVIDENCE, RHODE ISLAND, A CORPORATION OF NEW YORK.

GAS MIXER.

Application filed November 5, 1920. Serial No. 421,876.

To all whom it may concern:

Be it known that I, GEORGE S. BARROWS, a citizen of the United States, residing at Providence, in the county of Providence and 5 State of Rhode Island, have invented certain new and useful Improvements in Gas Mixers, of which the following is a specification.

This invention relates to improvements in gas mixers.

10 The industrial uses of a gas flame, which are many and important, frequently require that a variation be made either in the body of the flame or in the constituent proportion of the gases. For economy of fuel and economy of workmen's time it has been appreciated that it would be highly useful to have apparatus by which the workman could extinguish the flame, or reduce it as desired, with a rapid motion, and restore it again 15 with equal speed, without having to burden himself with the relighting or with the delicacy of adjustment of proportions of gases upon restoring the flame; also to be able to reduce the total heat without reducing the 20 temperature of the flame, an ill result which ordinarily follows if he merely turns down the gas without reducing the supply of air, assuming that air is the oxidizing agent in use. It is another desirable feature to have 25 apparatus in which the physical mixture or distribution of gases through the flame is uniform, producing a flame which is uniform in all regions as regards temperature and perfection of combustion at all speeds of in- 30 flow.

The present invention has for its object the making of apparatus which shall have the above advantageous features, and those others which characterize the apparatus herein- 40 after set forth, among which are the ability to be set so as to produce any of a considerable range of different proportions of mixture, and to maintain the chosen proportions with approximate accuracy, whatever degree of 45 fullness of flame is desired. These objects are accomplished by providing a pair of valves similarly located, one in the supply pipe of each gas, with a lever or swing arm to operate each, and a master lever whose swing con- 50 trols both so that they swing in unison; and the connection between these two may by adjustment at various distances from the fulcrum be fixed so that a given movement of one valve will correspond to various proportional movements of the other valve. In the

specific form illustrated the operating arm for one of the valves, constitutes a lever actuating linkage to the other valve. The said pipes are arranged parallel to each other. Immediately after passing the valves, they 60 connect with a mixing shell, through the midst of which is a passage forming a continuation of one of the pipes, and around the periphery of which, surrounding the said passage, is another passage forming a continuation of the other pipe. These passages in the shell are separated by a conical wall through which are holes at intervals, drilled on axes oblique to the axis of the central passage. Assuming that air, which ordinarily 65 would be impelled under pressure, is connected to flow through the central passage, and combustible gas under pressure through the peripheral passage, it follows that upon the movement of the master lever the two valves 70 open in a pre-determined relation to each other, and that gas begins to circle around the air and to flow into the air current from all sides of it through said holes. If the shell pressure be low, because of the valves being 75 opened only to a small degree, the mixture will nevertheless be approximately uniform with that which occurs at higher pressure because the flowing of the air through the central passage has somewhat of an ejector 80 effect, so as to draw in the gas even from those parts of the peripheral passage which are remote from the place where gas enters 85 that passage.

It is intended that the patent shall cover, 90 by suitable expression in the appended claims, whatever features of patentable novelty exist in the invention disclosed.

In the accompanying drawings, which represent one embodiment of the invention;

95 Figure 1 is a plan showing the valves with linkage in closed position;

Figure 2 is a right end elevation, of the same, showing also the screw-stop means for limiting the closing of the valves;

100 Figure 3 is a left end elevation;

Figure 4 is a plan of the mixer shell in medial section; and

Figure 5 is a section on line 5—5 of Figure 2 showing the details of the adjustable 105 connection of the linkage.

Referring to the drawings, air which ordinarily may be under some degree of pressure is conducted through a supply pipe 10, to an air control valve 12 having gate 13; and 110

combustible gas ordinarily under slight pressure is supplied through a similar but preferably smaller pipe 14 to a gas control valve 16 having gate 17. These valves, which 5 may be of any suitable type, are here illustrated as being swinging gate valves of a well known style in which an internal arm that swings the gate is connected through gearing within to a short shaft passing out 10 through the valve casing and having outside a swing arm by which the shaft and gate are moved to open or close the valve. In the application of the invention herein illustrated, the inner details of the gate valves 15 are not shown but are to be understood as being located within the body casing 18 of the air valve and 20 of the gas valve, access to which may easily be had by unscrewing bolts 22 and 24 and removing covers 20 26 and 28 respectively. On the squared end 30 of the shaft projecting through the packing nut 32 of the air valve, is pinned the operating arm 34 of that valve which serves also as a lever by which the other valve may 25 be simultaneously moved. This arm is provided with a longitudinal slot 36 in which a block 38 may be moved, and fixed at various positions. A similar block 40 is similarly adjustable in a slot 42 which extends longitudinally in a link 44 whose other end is pivoted to the end of a swing arm 46, which is pinned on the squared end 48 of an operating shaft which extends in through 30 the packing nut 50 of the gas valve. The 35 adjustable blocks 38 and 40 are clamped securely in their respective slots by suitable means, which prevent their sliding in the slots but permit their rotation with respect to each other.

40 In Figure 5 is shown one form of such means in which the blocks 38 and 40 are separate sleeves mounted next to each other on a single pin 54 which passes through the slots 36 and 42 where those slots cross. This 45 sleeve 38 has a head portion which is too large to enter the slot 36, a neck portion which fits slidably in the slot and which is not quite equal to the lever 34 in thickness, and a stud 55 projecting on the other side of that lever, threaded and carrying a washer 56 and a nut 58. The lever can thus be clamped between the nut and said head portion of the sleeve, yet is free to turn with respect to the pivot pin, because the 50 sleeve is free to turn thereon. The other sleeve block 40 is likewise secured fast to the arm 44, and yet is free to turn about the pivot pin 54. These blocks are assembled on the pivot pin with their heads together, preferably with a little lubricant between them, and are held thus by cotter pins or other means at each end of the pivot pin. On loosening its clamping nut either block may be separately positioned in its 55 respective slot to vary the relative action

of the levers and hence of the valves; but the pivotal connecting pin 54 maintains the blocks in axial rotatable relation to each other. When the blocks are so fastened, a swing of the arm 34 produces a corresponding movement of the arm 46, the handle 34 constituting a lever for that purpose with the shaft 30 acting as fulcrum, though the degree of movement of the arm 46 may be quite different from that of the arm 34 depending upon the position of the blocks in the slots of the handle and connecting link. Setting the block 38 out or in along slot 36 in the arm 34 will produce more or less motion of arm 46 when the swing occurs, 75 that is, more or less coincident change of setting of valve 16. Setting the block 40 nearer to or farther from the arm 46, along link 44, will change the degree to which one valve stands open when the other is at any 80 given degree of opening, that is, change the zero point. Handle 34 thus operates both valves simultaneously. Because of this adjustability a wide range of relative valve openings may be had. A stop screw 60, 90 passing through the swing arm 46, may be adjusted to strike the casing of the valve 16 thereby limiting the closure. This has utility where it is desired to prevent the flame from being extinguished, leaving it 95 burning low and ready instantly in larger volume upon the opposite swinging of the lever. When once he has adjusted this screw for this purpose, the workman can operate the handle rapidly in either direction, without particular care and without fear of entirely shutting off the flame.

A mixer shell 62, connected closely to the air valve 12 by a short nipple 64, has a central cylindrical passage through which 105 the air passes direct to a mixing chamber 65. Surrounding this central passage is an annular chamber 66 formed by the passage wall and the exterior wall of the shell, into which the gas from valve 16 is conducted by an 110 elbow 68. This annular chamber 66 is separated from the mixing chamber 65 by a conical partition 70 through which holes 72 are drilled obliquely to the axis of the central passage, and through which the gas enters 115 the mixing chamber and joins the air. The induction of gas to the current of air in separated jets on all sides of the air makes a mixture which is approximately uniform, because of that separation and distribution 120 of jets from the very instant of gas first meeting the air. Hence the mixing chamber 65 can be very short, and its exit 74, which is of greater diameter than the central passage through the shell so as to accommodate 125 the combined volumes of the components of the mixed gas, may be connected to a burner 76 of any desired type. The mixing is facilitated however by the fact that at the place where the gases are first mingled, by 130

jets of one passing through said holes into the moving current of the other gas, the said central passage has conical expanding walls through which the holes pass perpendicularly to the conical surface, and throw their jets forward obliquely toward the axis of the flow in the central passage. It results that the air which has entered chamber 65 is expanding along the cone and is the more readily penetrated by the jets of the combustible gas, which enter perpendicularly to the body of air at that point, yet pointing forward.

The operation of the mixer is exceedingly simple. A slight throw of the handle 34 turns on or off, or increases or decreases, the supply of both gases; and the apparatus maintains the proportion of one gas to the other approximately constant as predetermined from time to time, by the setting of the linkage.

In manufacture it is an advantage that the mixing chamber is so short for the holes 72 can in consequence be drilled by a tool 25 inserted through the discharge end 74.

I claim as my invention:

1. A gas mixer having a shell with central passage, and an annular passage around it, beyond which the central passage has a mixing and delivery portion adapted to lead to a burner; the whole being arranged with a wall between said central passage and the annular passage, near an open end of the passage, oblique to the axis of the central 30 passage, and provided with a multiplicity of holes formed on axes normal to said oblique wall, and pointing substantially in radial planes toward said axis, located in different directions from said axis and at distances from the said open end of the passage such that the said axes of holes pass out through the open end, through which openings the gas is jetted from the annular passage into the central passage.

45 2. A gas mixer comprising a shell with central passage and an annular passage around the central passage, having a series of openings thereinto distributed therearound; the central passage beyond said 50 openings being adapted to lead the gases to a burner while being mixed in said passage beyond; inlets of the shell, leading respectively to the said annular and central passages, arranged with their axes parallel and 55 adapted for pipe connections, whereby the shell holds rigidly the pipes so connected; and a pair of valves at said entrances, set on said parallel axes, having swinging arms,

connecting linkage and a single operating arm, whereby they move simultaneously and proportionately.

3. A gas mixer having a shell with combination of three tubular passages; comprising two inlet passages for separate gases and a single outlet passage for the mixture 65 thereof; valves at the said inlets; and unitary means controlling them whereby they move simultaneously and proportionately to vary the said inlet passages thereby maintaining the mixture in said shell in predetermined proportions.

4. A gas mixer comprising a shell with a central inlet passage; an annular inlet passage therearound, having a series of openings into the central passage, beyond which the said central passage becomes a common outlet; valves, one controlling each inlet passage of the shell; and unitary means for moving said valves simultaneously and proportionately.

5. A gas mixer comprising, in combination, a mixing chamber, separate gas passages leading thereto, a valve with swinging arm for each separate passage, and a link connecting them; one of said arms being prolonged beyond the point of connection, thereby constituting a lever for operating the other arm; there being a lug on one arm adapted to engage a fixed part and thereby to stop the closing swing of the 90 system before the valves are closed.

6. A gas mixer comprising, in combination, a mixing chamber, separate gas passages leading thereto, each having a valve with swinging arm; and a link connecting the said arms, there being crossed slots provided in the link and in one of said arms, and screw clamping sleeves, arranged on a common pivot pin about which they may separately rotate, each passing through one of 100 the slots and adapted to clamp the link or arm in which its slot is.

7. A gas mixer comprising, in combination, a mixing chamber, separate gas passages leading thereto, each having a valve 105 with swinging arm; and a link connecting the said arms, there being crossed slots provided in the link and in one of said arms, and screw clamps, one passing through each slot, having a common axis about which one 110 clamp may rotate relative to the other while both are in their several slots.

Signed at Providence, Rhode Island, this twenty-seventh day of October, 1920.

GEORGE S. BARROWS.
